UNITED STATES PATENT OFFICE.

JAMES E. GOALEN, OF SALT LAKE CITY, UTAH.

ROTARY INTERNAL-COMBUSTION ENGINE.

Application filed October 14, 1924. Serial No. 743,568.

This invention relates to improvements in internal combustion engines.

The primary object of this invention is the provision of an internal combustion engine embodying a rotary piston arrangement which operates on a novel principle to generate great horse power in proportion to the weight of the engine.

A further object of this invention is the provision of a novel internal combustion engine embodying a rotor and a stator, with novel means for compressing fuel charges and rendering the force of the explosion entirely effective to move the rotor in one direction.

A further object of this invention is the provision of novel fuel control means for rotary internal combustion engines.

Other objects and advantages of this invention will be apparent during the course of the following detailed description.

In the accompanying drawings, forming a part of this specification, and wherein similar reference characters designate corresponding parts throughout the several views,

Figure 1 is a longitudinal cross sectional view taken through the improved internal combustion engine, showing operating details thereof.

Figure 2 is a cross sectional view taken transversely of the section illustrated in Figure 1, showing certain details of the invention in side elevation.

Figure 3 is a cross sectional view taken substantially on the line 3—3 of Figure 2.

In the drawings, wherein for the purpose of illustration is shown only the preferred embodiment of this invention, the letter A may generally designate the improved internal combustion engine, which may include a stator B; rotor construction C; and fuel and explosion controlling means D.

The stator B preferably consists of the housing 15, formed of sections 16 and 17 which are annularly bolted together, as at 19, to provide the substantially cylindrical shaped compartment 22 within which the rotor C is disposed. The sections 16 and 17 are similarly formed, and are bolted on the medial line of the housing 15, as to permit the easy assemblage of the piston and rotor arrangement. Hubs 23 and 24 are provided on the housing sections 16 and 17 respectively, concentric with the compartment 22,

with passageways therethrough for rotatably receiving the shaft 25 of the rotor C, as will be subsequently described.

The housing 15, therebelow, provides a base or supporting platform 27, parts of which base are provided on each of the sections 16 and 17, and of as light a construction as possible, preferably being of cast metal and of sufficient area to properly support the engine and permit its bolting or other attachment to a supporting surface or foundation.

The housing 15 provides an exhaust passageway 30 tangentially arranged with respect to the compartment 22, having communication with said compartment by a series of openings 31 in the wall which forms the compartment 22. This passageway 30 leads downwardly through the base 27, to any approved location, such as is illustrated in Figure 1 of the drawings. At the opposite side of the center of the housing 15 from the exhaust passageway 30, a reservoir 35 is provided in the base 27, adapted to receive a body of lubricating oil 36. The wall 37 of the housing 15 which forms the compartment 22 is provided with a series of openings 38 which communicate with the reservoir compartment in which the oil 36 is disposed, and these perforations continue through the wall 37, at the lowest part of the compartment 22, so that a small portion of the body of oil may enter the compartment 22 and be splashed or picked up by the rotor mechanism as the same moves within the compartment 22. The openings 38 continue upwardly about one side of the wall 37, so that any excess lubricant picked up by the rotor may drop back into the reservoir 35. A filler construction 40, preferably of tubular formation, is provided in the housing 15, immediately above the base 27, as is illustrated in Figure 1 of the drawings. The oil level may be determined by any suitable float mechanism 42, as is illustrated in Figure 1 of the drawings.

The housing or stator B preferably includes the radially extending cooling vanes or flanges 45, although in lieu of an air cooled engine the same may be water cooled, and appropriate water manifolds or jackets provided for the housing about the compartment 22 within which the rotor operates. A screw threaded opening 46 is provided

through the housing 15, in any approved location, adapted to receive a spark plug 46 of any approved type, for the purpose of exploding a fuel charge at the proper point in the compartment 22, between certain co-operating parts of the rotor mechanism C, as will be subsequently mentioned.

The rotor structure C preferably includes the shaft 25 above mentioned, which bears in the hubs 23 and 24, extending concentrically through the compartment 22. Within the compartment 22 the rotor includes the + shaped piston structure 50, which includes a central portion 51 keyed, as at 52, to the shaft 25, and preferably including four pistons 53, 54, 55 and 56 radiating from the shaft and rigid with the portion 51. These pistons are preferably 90° apart, and are substantially in the form of the conventional horseshoe, the same being grooved inwardly of the outer surfaces thereof to support the substantially U-shaped piston rings 58, as illustrated in the drawings. These piston rings 58 at the outer circumferences of the pistons slide in abutment with the inside surfaces defining compartment 22. Within the compartment 22, and preferably fixed with the shaft 25, it is preferred to provide a pair of plates 60 and 61, at opposite sides of the compartment 22, concentric with the shaft 25, and the inner end of the pistons and the piston rings supported thereby engage the facing surfaces of these plates 60 and 61 in a fluid tight engagement.

The rotor C furthermore includes in each of the 90° spaces between adjacent pistons a member 65. Four of these members are, of course, provided, and they are pivotally mounted upon pins or shafts 66 which are transversely carried by the plates 60 and 61. The members 65 may appropriately be termed paddles, and they are somewhat in the form of the pistons of the rotor, being substantially horseshoe-shaped in formation, and circumferentially grooved to receive substantially U-shaped packing rings 69. Due to the eccentric pivoting of the paddles in the stator casing, a leak-proof connection could not be maintained without the use of rings 69, which are of the conventional expansion type and compensate for such eccentric mounting of the paddles. These members 65 are limited in the amplitude of movement toward rearwardly adjacent pistons, by means of an abutment 70 provided on the facing side of each rearmost adjacent piston, providing a radial surface 71 against which the members may rest during rotation of the piston mechanism, and until the members are displaced in succession for the purpose of compressing fuel charges and assisting in rotation of the rotor in the proper directions.

On the rearmost face of each of the pivoted members 65, an abutment 75 is pro-

vided, which provides a surface 76 tangentially arranged with respect to the shaft 25, and providing a notch 77 therein. A plunger mechanism 79 to be subsequently described cooperates over this tangentially disposed surface 76 and in the notch 77 to properly move the member 65 for the purpose of compressing a fuel charge just before the power stroke.

Referring to the mechanism D, the same preferably includes a rocker arm 80, pivotally mounted intermediate its ends on a shaft 81; this shaft being carried by a standard or post 82 appropriately affixed to the housing 15 in any approved manner, upwardly thereon. This rocker arm 80 is of Y-shaped formation, including the bifurcated end providing arms 83 and 84, respectively operatively connected with the plunger mechanism 79 and fuel pump 86. At the opposite side of the shaft 81 the rocker 80 includes the arm 87.

The rocker arm 80 is of course synchronously operated with the shaft 25, and is connected thereto in any approved manner. The preferred method of construction contemplates the provision of a casing 88 laterally of the housing 15, providing a compartment 89 adapted to receive a body of lubricant, if desired. Filler and drain structures 90 and 91 may be provided respectively for this casing 88. The shaft 25 passes through the compartment 89, and extends through a packer nut structure 92. In the compartment 89 a relatively large gear 93 is provided on the shaft 25, in meshing relation with the smaller gear 94 carried by a counter shaft 95. The counter shaft 95 is suitably provided with an eccentric 96, and from the eccentric 96 a connecting rod 97 extends for connection to the outer end of the rocker arm portion 87.

The housing 15 upwardly thereon supports a tubular extension 100, with a valve seating flange 101 therein, upon which a check valve structure 102 is seated, spring operated so that the passageway 103 through the extension 100 is normally closed from the compartment 22 of the housing 15. Upwardly on the extension 100 the pump casing 103 is detachably mounted, through which an intake conduit 104 communicates, above the check valve 102. This intake conduit 104 leads from any suitable carbureting device, and may have a check or control valve 105 therein, for the purpose of regulating the flow of the fuel from the carbureting device into the compartment 106 of the casing 103. The pump 86 is in the form of a piston, and operates in the compartment 106 above the intake 104, and of course above the check valve 102, so that upon rocking of the arm 80, the piston or pump arrangement 86 will compress the vaporized fuel and unseat the valve 102 for the purpose of forcing

fuel into the stator compartment 22 between any piston and its cooperating member 65, which happens to be in alignment with the passageway 103^a.

5 Immediately adjacent the extension 100, and parallel therewith, is an extension 110, within which the plunger 79 is reciprocably mounted. A cap 111 is detachably provided as part of the extension 110, having an oil 10 conduit connection 112 for lubricating the passageway in which the plunger 79 slides. At its lower end the plunger 79 supports a roller 113 which is adapted to roll over the inside surface 76 of the abutment 75 of each 15 of the members 65, as the same come into operating engagement incident to rocking of the arm 80.

In operation, it is to be noted that the rotor and the plunger and fuel inlet mechanisms are synchronously operated, incident 20 to their connection with the shaft 25. The fuel will be inlet through the passageway 103^a in proper timing with operation of the rotor mechanism, and permit a sufficient 25 quantity of the vaporized fuel to pass as a charge into the compartment between any pistons and its adjacent member 65, which as above mentioned, happens to be in alignment with the passageway 103^a. In this fuel 30 receiving position the member 65 is in abutment against the inclined face 71 of the next rearwardly positioned piston. As the rotor continues to operate, after having received a fuel charge the member 65 in the compartment 35 which has received the fuel charge passes the plunger mechanism 79, and immediately having passed the same the plunger mechanism 79 descends so that the roller 113, rolling against the inclined face 76 will 40 force the pivoted member 65 forwardly off its abutment 70, as is illustrated in Figure 1, and compressing the fuel charge immediately forward of this member 65, which has been moved by the plunger 79. This compression 45 is caused because of the fact that the member 65 is moved by the plunger 79 faster than the rotation of the pistons. As this compression takes place, and when it has received the maximum compression effect, 50 the spark from the plug 46 ignites the fuel charge, and the rotor receives the force of the explosion to impel the same. The force of the explosion may only be exerted in one direction about the shaft axis, because of the 55 fact that when the explosion takes place the plunger roller 113 still is resting on the abutment 75, preferably in the notch 77, of the inclined surface 76, and holding the member 65 against movement counter to the direction 60 of rotation of the rotor. The exploding gases incident to their expansion will then, of course, force the rotor in the clock-wise direction illustrated in the drawings.

65 After the explosion has taken place in the

compartment between any piston and its cooperating pivoted member 65, the exploded gases having expanded to permit the work to be performed, the member 65 of course moves back against its abutment 70 of the adjacent rearmost piston, and in this position the exploded gases are permitted to exhaust through the openings 31 and into the exhaust passageway 30. As the rotor pistons move past the exhaust openings 31, they will pick up a quantity of the oil which is in the lowermost portion of the compartment 22, for the purpose of furnishing lubricant to the sliding surfaces of the pistons in the housing 15. Any excess lubricant caught up by the pistons and the pivoted members 65, will be permitted to drain through the openings 38 which are provided for a considerable distance upwardly along one side of the housing 15, and as illustrated in Figure 1 of the drawings.

The outer end of the shaft 25 may be suitably provided with a pulley wheel 120, for connection to a generator or the like, and a gear 121 may be provided for connection to suitable distributing mechanism. Other mechanisms may be provided for the internal combustion engine, in accordance with well known constructions, and the carbureting device may be of any approved character, suitable to provide a vaporized fuel to the intake 104.

From the foregoing description of this invention it is apparent that a novel type of 100 rotary internal combustion engine has been provided, which is very efficient in operation, incident to the novel synchronizing cooperation of the piston mechanism of the rotor, and the plunger means for maintaining the pivoted members of the rotor mechanism, so that the force of the explosion is fully 105 transmitted to the rotor mechanism for impelling it in one direction about the shaft axis of the rotor. The fuel inlet valve mechanism being also synchronously connected with the rotor shaft, permits an accurate feeding of fuel into the rotor mechanism compartment, in advance of the power stroke, so that a quick succession of power 110 strokes may take place on the rotor mechanism. Of course, any number of the devices 115 may be employed in connection with the shaft 25.

Various changes in the shape, size, and arrangement of parts of the improved internal combustion engine herein shown and described, may be made to the form of the invention without departing from the spirit of the same or the scope of the claims.

I claim:

1. In an engine of the class described the combination of a housing providing a compartment therein, rotor means in said compartment providing a plurality of fuel receiving chambers, pivoted members in each

of said fuel receiving chambers independently connected for rotation with said rotor means, and means cooperating individually with said pivoted members to move them and compress fuel charges prior to an explosion and to hold them after explosion to permit force of the explosion driving said rotor means in one direction only.

2. In an internal combustion engine of 10 the class described the combination of a stator housing including a compartment therein, a shaft extending through said compartment, a rotor carried by said shaft including a plurality of laterally extending spaced 15 blades operating in said compartment to subdivide the compartment into a plurality of non-communicating chambers, members independently pivoted in said chambers between the adjacent blades and extending 20 transversely of their respective chambers to subdivide said chambers, said members acting in piston-like manner to prevent communication of the spaces at opposite sides thereof, fuel inlet means to supply fuel to said 25 chambers between a movable member in the chamber and an adjacent blade, means for independently moving said members at predetermined times toward adjacent blades to compress fuel charges therebetween, and 30 means for exploding said fuel charge when so held under compression.

3. In a rotary internal combustion engine the combination of a stator providing a compartment therein, rotor means including piston blades operating in the compartment, pivoted piston-like members operating in said compartment rotatable with said rotor and pivoted with respect to the piston blades of the rotor, said piston-like members having 35 abutments thereon provided with tangentially arranged surfaces with respect to the rotor axis, and plunger means operating in said stator over said tangentially arranged surfaces of the piston members to move the 40 piston members relative to adjacent piston blades.

4. In an internal combustion engine the combination of a stator providing a substantially circular compartment therein, rotor 50 means including a shaft and radially extending piston-like blades operating in the compartment to subdivide the same into a plurality of chambers, a piston-like member pivotally carried in each of said chambers 55 and movable with respect to said piston blades and movable with respect to said rotor shaft, means for feeding of fuel into said chambers between a piston blade and an adjacent piston-like member, plunger means adapted 60 to move the piston-like members towards adjacent piston blades to compress a fuel charge and hold the piston like members against rotation in one direction, and means for exploding the fuel charge when so compressed to permit the force of the ex-

plosion to be exerted on the piston blade to send the rotor in one direction about its axis.

5. In a device of the class described the combination of a stator housing including 70 a compartment, a rotor in said compartment including a driven shaft and piston blades extending radially therefrom to subdivide the compartment into chambers, members pivotally carried in said chambers movable with respect to the piston blades and movable with said rotor about the shaft axis, means for supplying a fuel charge into each chamber at the proper time between a piston blade and its adjacent pivoted member, plunger means synchronously operated from said rotor to move the member for compressing a fuel charge between the same and an adjacent piston blade, and means for exploding a fuel charge when so compressed. 85

6. In a rotary internal combustion engine the combination of a stationary housing providing a compartment therein, rotor means for the compartment including a driven shaft and radially extending blades 90 acting as pistons in said compartment to subdivide the same into chambers, a pivoted piston-like member in each of said chambers between adjacent piston blades connected for rotation with said rotor shaft 95 and movable with respect to adjacent piston blades, fuel regulating mechanism synchronously operated from the rotor shaft for directing fuel into a proper chamber between a piston blade and its adjacent piston-like member, and means synchronously operated from said rotor shaft for moving the piston-like member toward an adjacent piston blade to compress a fuel charge therebetween and hold the piston-like member 100 against movement in direction counter to the direction of rotation of said rotor. 105

7. In a rotary internal combustion engine the combination of a stationary housing providing a compartment therein, rotor means for the compartment including a driven shaft and radially extending blades acting as pistons in said compartment to subdivide the same into chambers, a pivoted piston-like member in each of said chambers between adjacent piston blades connected for rotation with said rotor shaft and movable with respect to adjacent piston blades, fuel regulating mechanism synchronously operated from the rotor shaft for directing fuel into a proper chamber between a piston blade and its adjacent piston-like member, means synchronously operated from said rotor shaft for moving the piston-like member toward an adjacent piston blade to compress a fuel charge therebetween and hold the piston-like member against movement in direction counter to the direction of rotation of said rotor, means for exploding said fuel charge when so compressed, and means for 110 115 120 125 130

exhausting exhaust gases after explosion from said chambers.

8. In a rotary internal combustion engine the combination of a stationary housing including a compartment, rotor means in the compartment including blades subdividing the compartment into a plurality of non-communicating chambers, a rocker arm, means connecting the rocker arm for operation by said rotor, fuel inlet means for said chambers connected with said rocker arm, pivoted piston-like members in said chambers movable with said rotor and movable with respect to adjacent blades, and plunger mechanism operable preferably connected to said rocker arm for extension into said compartment at predetermined times for engaging said piston-like members and moving them towards an adjacent piston-like member to hold said piston-like member against movement counter to the direction of movement of the rotor.

9. In an internal combustion engine of the class described the combination of a stator providing a compartment therein, a rotor in the compartment including a shaft with a plurality of radially extending piston blades subdividing the compartment into a plurality of chambers, a pivoted member in each chamber movable with the rotor and movable with respect to adjacent piston blades in the chamber, means providing an abutment on the rear surface of each of said piston-like members having an inclined surface tangentially arranged with the rotor axis, means for inlet of fuel into said chambers between a piston blade and adjacent piston-like member of each of said chambers, a plunger, means connecting the plunger with said rotor so that it will synchronize with movement thereof and at predeter-

mined periods extend tangentially into the compartment of said housing for operating over the tangentially arranged surface of the abutment of a piston-like member whereby 45 to move the latter toward a forward piston member for the purpose of compressing the fuel charge in the chamber between said piston-like member being operated on and said piston blade, means for exploding a 50 fuel charge under such compression and means for exhausting exploded gases from said chambers.

10. In a motor of the class described the combination of a stator housing including a 55 compartment, a rotor in said compartment including a driven shaft and piston blades extending radially therefrom to subdivide the compartment into chambers, piston-like members pivotally carried in said chambers movable with respect to the piston blades and movably connected with said rotor for movement about the shaft axis with the rotor, means for supplying a fuel charge into the chamber at the proper 60 time between a piston blade and its adjacent pivoted member, means for limiting the movement of each pivoted member with respect to its adjacent rear piston blade so that the same will always be in a spaced relation, 65 cam means carried by the pivoted members, and plunger means operable in synchronism with the rotor to enter the chambers and engage said cam means at the proper time 70 to move a pivoted member towards an adjacent blade for compressing a fuel charge between the same and said adjacent piston blade, and means for exploding the fuel charge when so compressed and while the pivoted member is held by the plunger means 75 against movement in one direction.

JAMES E. GOALEN.
